CHOKER-LINE ATTACHMENT.

1,381,616.

Specification of Letters Patent. Patented June 14, 1921.

Application filed January 27, 1921. Serial No. 440,541.

To all whom it may concern:

Be it known that we, JULIUS C. CLAUSEN and JOHN BUCKLEY, both citizens of the United States, and both residents of Buckley Bay, in the Province of British Columbia, Canada, have invented certain new and useful Improvements in Choker-Line Attachments, of which the following is a specification.

10 Our invention relates to improvements in choker line attachments, and the object of our invention is to provide a simple, light, and strong device by means of which the choker line may be easily, quickly, and securely detachably connected to the hauling line, in logging operations, and by the use of which labor is lightened and much time saved since the device is comparatively light, is very easy to handle, and cannot become 15 inadvertently detached.

We attain this object by the construction illustrated in the accompanying drawings in which—

Figure 1 is a face view of the device.

25 Fig. 2 is a face view, in part section, Fig. 3 is a side view.

Fig. 4 is a fragmentary side view, in section.

Fig. 5 is a plan view.

30 Fig. 6 is a view illustrating the practical application of the invention.

Similar figures of reference indicate similar parts throughout the several views.

The device consists of a very strong plate 35 1, preferably longer than it is wide, the upper end of which is provided with an eye 2 to which the hauling line 3 is secured while its lower end is turned outwardly at right angles to the body of the plate, as at 4, and is slotted from the back of the plate to within a short distance of the outer end of the portion 4, the slot being indicated by the numeral 5, and this slot is carried longitudinally of the plate, as at 6, to about its mid-

40 length where it terminates in an annular opening 7 of greater diameter than the width of the slot, from which it will be seen that the plate is thus provided with the opening 7 having a gap 8 in one side from

45 which gap the slot 6 extends longitudinally into the portion 4 where it is turned at right angles, so that the portion 4 forms in effect an eye, all as shown in Figs. 1, 3, and 5.

50 Within the body of the plate concentrically 55 of the opening 7, a circumferential groove 9

is formed by recessing the periphery of the opening about its midwidth, in which groove is rotatably mounted a ring 10 having divided ends 11 and 12 spread apart a distance substantially equal to the width of the gap 8 hereinbefore mentioned, one of the ends being bent, as at 13, to provide a means for manually rotating the ring.

14 indicates the choker line which is provided at both ends with knobs 15 and 16 respectively the diameter of which is less than the diameter of the opening 7 but greater than the width of the slot 6. One of the knobs may be dispensed with and the end provided with an ordinary hook and swivel, 65 if desired.

15 The manner in which the device is used will be readily apparent on reference being had to the drawings, particularly Fig. 6, and may be briefly described. The hauling line 3 being secured to the eye 2 and it being desired to connect the choker line all that is necessary is to pass the knob 15 through the opening 7 from the back of the plate, the ring 10 being first of all rotated to bring 75 the space between its divided ends 11 and 12 into registration with the gap 8, as shown in Fig. 1, and then pass the line through the gap and along the slot 6, after which the ring is rotated so that the undivided portion 80 straddles the gap, as shown in Fig. 2, and thus the line can not become inadvertently detached from the plate. The strain on the line when attached to an object such as a log, and under load, seats the knob 15 85 against the portion 4 so that it is held in place in an efficient manner.

90 From the foregoing it will be seen that we have devised a simple means for attaching choker lines to hauling lines, or for other 95 analogous purposes, which is practical, efficient, and of great convenience to those engaged in logging or hauling operations.

99 What we claim as our invention is:—
1. A choker line attachment comprising 100 a plate adapted at one end for connection to a hauling line, said plate being provided with an aperture and a slot extending from said aperture, and means for closing the entrance to said slot.

105 2. A choker line attachment comprising a plate adapted at one end for connection to a hauling line, said plate being provided with an annular aperture intermediate its length and a slot extending from said aperture, the 110

periphery of said aperture being recessed to form an annular groove, and a ring rotatably seated in said groove having divided ends spread apart a distance substantially equal to the width of said slot.

3. In a device of the character described, a choker line having a knob on one end, and a plate adapted for attachment to a hauling line, said plate being provided with an aperture of greater diameter than the said knob and a slot extending from the aperture of less width than the knob and wider than the line diameter.

4. In a device of the character described, a choker line having a knob on one end, a plate adapted for attachment to a hauling line, said plate being provided with an aperture of greater diameter than said knob and a slot extending from the aperture of less width than the knob and wider than the line diameter, and means for closing the entrance to said slot.

5. In a device of the character described, a choker line having a knob on one end, a

plate eyed at one end and turned at its opposite end at right angles to the body, said plate being provided with an aperture of greater diameter than the said knob and a slot of less width than the knob and wider than the line diameter extending from the aperture through the right angled end, and a ring rotatably mounted on said plate concentrically of said aperture having divided ends forming a gap through which said line may be passed.

6. A choker line attachment comprising a plate provided with a slot and an aperture into which said slot opens at one end, and a split ring rotatably mounted by the plate and controlling communication between the slot and aperture, said ring having one end thereof formed to present an operating knob.

Dated at Buckley Bay, B. C., this 27 day of Dec., 1920.

JULIUS C. CLAUSEN.
JOHN BUCKLEY.
